UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

OPERATING MECHANISM FOR CAR-DOORS.

1,192,986.

Specification of Letters Patent.

Patented Aug. 1, 1916.

Application filed February 11, 1916. Serial No. 77,620.

To all whom it may concern:

Be it known that I, ARGYLE CAMPBELL, a citizen of the United States, residing at Chicago, in the county of Cook and State 5 of Illinois, have invented a certain new and useful Improvement in Operating Mechanism for Car-Doors, of which the following is a full, clear, concise, and exact description, reference being had to the accompanying 10 drawings, forming a part of this specification.

This invention relates to improvements in operating mechanism for car doors.

One object of the invention is to provide 15 a simple, cheap and efficient arrangement of the locking means for car door and other operating shafts of a similar nature.

Another object of the invention is to provide 20 means on a pawl which coöperates with a ratchet and on the lock or dog which coöperates with the pawl so arranged that said pawl and lock may be readily operated by the same claw bar or other tool used in operating the shaft. In addition, the parts 25 are so arranged that the shaft, pawl and lock are rotated in the same direction when opening the doors or closing the doors, thereby facilitating the operations.

The invention furthermore consists in improvements in the parts and devices and in 30 the novel combinations of the parts and devices herein shown, described or claimed.

In the drawing forming a part of this specification, Figure 1 is a side elevation of 35 a portion of a dump car illustrating my improvements applied thereto. Fig. 2 is a transverse, sectional view of a portion of a car and taken approximately on the line 2-2 of Fig. 1. Fig. 3 is a detail, sectional 40 view taken substantially on the line 3-3 of Fig. 1 and illustrating more particularly the method of mounting the pawl and lock, and Figs. 4 and 5 are detail sectional views corresponding substantially to Fig. 3 45 and illustrating two different embodiments of my invention.

In said drawing, 10 denotes the side wall of a car having a depending plate 11 secured thereto. On the inner side of 50 the plate 11 is secured by rivets a casting 12 having an inwardly extended bearing 13 for a casting 14 secured to the squared end of the transversely extending door operating shaft 15. The shaft 15,

at its inner end, is mounted in suitable bearing brackets 16-16 secured to the inner sides of the center sills 17-17, 18-18 denoting chain winding drums from which chains (not shown) extend to the other parts of the door operating mechanism. 55 The casting 14 is provided at its outer end with an integral ratchet wheel 19 and on the interior thereof is provided with a thread 20 with which coöperates a lug 21 formed on a casting 22 having a squared 60 outer end 23 by which it is adapted to be operated by a claw bar. The member 22 is permitted substantially an entire revolution relative to the casting 14 to thereby obtain sufficient lost motion in releasing the door 65 operating mechanism and prevent injury to the operator.

The casting 12 is provided with a hub 24 suitably cored to receive a pin 25 having a shoulder 26 and threaded inner end 27, 75 whereby said pin may be held in fixed position by a nut 28 and lock nut 29. The pin 25 extends to the outer side of the plate 11 and has pivotally mounted thereon a pawl 30 adapted to coöperate with the ratchet 80 wheel 19. The pawl 30 on its outer side, is provided with an integral squared section 31 of the same size as the squared end 23. The casting 12 is further provided with a hub 32 cored similarly to the hub 24 and 85 having mounted therein a headed pin 33 similar to the pin 25. The pin 33 has pivotally mounted thereon a cam shaped dog or lock 34 which coöperates with the tail piece 35 on the pawl 30. The dog or lock 90 34 is also provided with a squared section 36 of the same size as the other squared sections 31 and 23. The rivets indicated at 40-40 are suitably countersunk in order to prevent interference with the pawl and lock 95 when the latter are rotated.

The parts are shown in locked position and in order to release the car doors, the dog or lock 34 is rotated in a counter-clockwise direction by a claw bar applied to the 100 squared section 36; the pawl is then released by rotating the same in a counter clockwise direction by the same claw bar; and finally the shaft 15 is rotated by applying the claw bar to the squared end of the casting 22 and 105 rotating it in a counter-clockwise direction.

To close the car doors and lock the shaft 15, it is apparent that the reverse of the

above described operations will be required, all three members being rotated at this time in a clockwise direction.

In the modification shown in Fig. 4, the 5 casting 112 is the same as that illustrated in Figs. 1, 2 and 3, but instead of employing pins for the pawl and dog, the latter are each provided with an integral, shouldered, rounded extension 126 and a reduced end 10 127, the latter receiving a cotter pin 128 therethrough. From this description, it will be seen that the pawl and dog may each oscillate or pivot in substantially the same manner as the corresponding parts illustrated in Figs. 1, 2 and 3.

In the modification shown in Fig. 5, the casting 212 instead of being provided with shouldered recesses to receive the pins and extensions of the pawl and dog previously 20 described, is provided with integral arms or pins 225 which pass through the depending plate 211 to the outer side of the latter and have rotatably or oscillatably mounted thereon the pawl 230, the latter being retained in position by a cotter or other suitable means 228. As will be understood, Figs. 4 and 5 illustrate merely the modifications for the pawl but the mountings of the dog will correspond thereto in each instance.

30 From the preceding description, it will be seen that the workman can operate the lock, pawl and shaft in the most efficient manner and without having to shift his position since the claw bar will always be 35 manipulated in the same direction during opening of the doors and vice versa when the doors are closed. Furthermore, by providing the squared sections 31 and 36 on the pawl and lock, which are similar to the 40 squared end of the shaft, sledging or mutilation of the pawl and lock which has heretofore been customary, will be avoided and thereby the life of the parts increased.

I claim:

45 1. In mechanism of the character described, the combination with an operating shaft having a locking member on the end thereof, of means coöperating with said locking member to lock the shaft in position, 50 said means including a pawl pivoted about an axis parallel with the axis of said shaft and coöperable with said locking member, and a dog engageable with said pawl and also pivoted about an axis parallel with the 55 axis of said shaft, said shaft, pawl and dog being each provided with an integral squared portion of the same size, said shaft, pawl and dog being all rotated in the same direction to release the operating shaft.

2. In mechanism of the character de- 60 scribed, the combination with a shaft hav- 65 ing a ratchet wheel thereon, of a pivoted pawl coöperating with said ratchet wheel, and a lock coöperating with said pawl, said pawl and lock each having formed inte- 70 grally therewith similar members each adapted to detachably receive the same operating tool, said shaft, pawl and lock being all rotated in the same direction when the shaft is being released or moved to locked 75 position.

3. In mechanism of the character de- 80 scribed, the combination with a casting hav- 85 ing a bearing and two cored hubs, of a shaft rotatably mounted in said bearing, shoul- 90 dered pins mounted in said cored hubs and rigidly attached to said casting, a pawl pivotally mounted on one of said pins, and a lock pivotally mounted on the other of said pins.

4. In mechanism of the character de- 95 scribed, the combination with an operating shaft having a ratchet wheel fixedly asso- 100 ciated therewith and a member relatively rotatably associated with said ratchet wheel, said member having a squared operating end, of a pawl coöperating with said ratchet wheel and having a squared operating section, and a dog coöperable with said pawl and having also a squared operating section, 90 said member, pawl and dog being all rotated in the same direction to effect the un- 105 winding movement of the shaft.

5. In a mechanism of the character de- 95 scribed, the combination with a casting 100 adapted to be secured to a portion of a car, said casting being provided with a bearing 105 for a shaft, of a pawl adapted to coöperate with said shaft, a dog adapted to coöperate with said pawl and means for pivotally at- 110 taching said pawl and dog to said casting.

6. In a mechanism of the character de- 115 scribed, the combination with a casting adapted to be secured to a portion of a car, said casting being provided with a bearing 110 for a shaft, of a pawl adapted to coöperate with said shaft, a dog adapted to coöperate with said pawl and means for pivotally at- 115 taching said pawl and dog to said casting, said means including shouldered sockets 110 formed in said casting and correspondingly shouldered members extending inwardly from said pawl and dog into said sockets and fitting the latter.

In witness that I claim the foregoing I have hereunto subscribed my name this 7th day of February, 1916.

ARGYLE CAMPBELL.
